G. Fleming,

Derrick.

No. 100,613.

Patented Mar. 8, 1870.

UNITED STATES PATENT OFFICE.

GEORGE FLEMING, OF NEW YORK, N. Y.

IMPROVEMENT IN POLE-ASCENDING APPARATUS.

Specification forming part of Letters Patent No. 100,613, dated March 8, 1870.

To all whom it may concern:

Be it known that I, GEORGE FLEMING, of the city, county, and State of New York, have invented a new and Improved Pole-Ascending Apparatus; and I do hereby declare that the following is a full, clear, and exact description thereof, which will enable others skilled in the art to make and use the same, reference being had to the accompanying drawings, forming part of this specification.

This invention relates to improvements in apparatus for ascending telegraph and other poles; and it consists in an arrangement of rigging for hoisting masts up by the side of the poles, on the top of which masts are carried pulleys and cords, the latter hanging to the ground, by which cords with pulley-blocks are swung over the arms of the poles, through which pulley-blocks the cords of the platform are rove, by which a person may be drawn up.

It also consists in an improved rigging for attaching to the top of the pole for suspending the pulley for the platform, for use when the pole has no arm at the top over which the cord can be swung.

Figure 1 is an elevation of the pole and riggings, showing the manner of holding the mast. Fig. 2 is an elevation of the same when the rigging is up. Fig. 3 is an elevation of a part of a pole, and the rigging used on poles not having arms; and Fig. 4 is a detail view of a part of the said rigging shown in Fig. 3.

A represents a telegraph-pole with arms B at the top.

C is a light mast, which may be either in sections c' and c'', with extension-rigging for sliding the sections on each other to extend the length after it is raised, or it may consist of one light pole, if preferred. The lower end is provided with a point, D, to act either on the telegraph or other pole or on the ground as a step to prevent slipping.

E is a cord attached to the mast a suitable distance above the foot—say at or near the top of the first joint, when made in sections. It is passed around the pole A and back to the mast, where it passes over a pulley, F, and then is taken in the hands of the attendant. This cord is adjusted when the mast is lying on the ground, and at that time passes around the pole A at the base or a short distance above it. The top end of the mast being raised as high as it can well be by a man standing

on the ground, the cord E is then drawn up, and has such action on the mast as to force it up into a vertical position parallel with the pole, where it is made fast by fastening the cord E, the part of which going around the pole slips along up it as the mast rises. This mast carries an arm, G, at the top, which has a grooved pulley, H, suspended at the end, over which a cord, I, with a weight, K, is suspended, so as to be carried up by it and swung over the arm B of the pole, after which the mast is lowered away, leaving the cord I on the arm, by which a cord, K', having a pulley-block, L, in which the cord M of a platform, N, is suspended, is drawn up to the arm B, and secured by making the cord K' fast to the pole A at the lower end, so that the platform may be hoisted up for the ascension of the pole by a man thereon, the platform being hoisted by a man on the ground and by the assistance of the one on the platform, both pulling on the part O of the cord M. After the object of the ascent of the pole is accomplished and the platform let down the cord K' is loosened from the pole A and drawn back over the arm B.

For applying and securing the pulley-block L for the platform-hoisting cord M to poles not having arms at the top, I have provided a cap, P, of cords suited in shape and arrangement to be engaged with the pointed tops of such poles by being dropped upon them from above, having a block, L, with the cord M rove through it, a binding-cord, Q, a tripping-cord, R, and a tripping-wedge, S, attached as shown in Fig. 3, which cap I drop on the top of the pole by means of the mast and cord I, the latter being attached to the loop T for suspending it. When it is dropped on the pole the cord Q is drawn down tightly by the side of the said pole, and made fast thereto at the bottom for holding the cap against being drawn off by the action of the platform-cords M, it being adjusted to the opposite side of the pole A.

When the operator is about to descend from the pole he adjusts the trip-cord R over the top of the tripping-wedge S, which is grooved or notched for holding it, as shown in dotted lines S', by which, when ready for removing the cap, he pulls the top of the wedge down over the pointed end of the pole after loosening the cord Q, throwing the bottom of the cap

up, and casting the whole off, as will be clearly understood by inspection of the drawings.

The telegraph and other high poles are now commonly ascended by means of strong spurs attached to the feet and legs of the climber, and thrust into the wood on opposite sides as the feet and legs are raised or lowered, which is, besides being very laborious, very damaging to the poles, which decay rapidly in consequence of penetration of the rain, and the action of the air and temperature.

Having thus described my invention, I claim as new and desire to secure by Letters Patent—

1. The combination, with a pole or mast, *c*, either made in section and provided with extension-rigging or not, of the arms *G*, pulley *H*, hoisting-cord *E*, and pulley *F*, all arranged for operation substantially as specified.

2. The combination, with a cap, *P*, adapted for application to the top of a pole by dropping thereon from above, of the pulley-block *L*, cord *M*, tripping-cord *R*, and tripping-wedge *S*, all substantially as specified.

3. The combination, with a mast having an arm, *G*, and pulley *H*, arranged as described, of the weighted cord *I*, the cap *P*, and its binding and tripping apparatus, substantially as specified.

The above specification of my invention signed by me this 27th day of January, 1870.

GEORGE FLEMING.
